UNITED STATES PATENT OFFICE.

JAMES HILTON, OF NEWARK, NEW JERSEY.

TROWEL.

SPECIFICATION forming part of Letters Patent No. 593,770, dated November 16, 1897.

Application filed April 7, 1897. Serial No. 631,129. (No model.)

To all whom it may concern:

Be it known that I, JAMES HILTON, a citizen of the United States, residing at Newark, county of Essex, State of New Jersey, have invented certain new and useful Improvements in Detachable Handles for Trowels, fully described and represented in the following specification and the accompanying drawings, forming a part of the same.

10 The object of this invention is primarily to furnish an improved means of attaching a handle to the trowel-blade without springing the blade. This is effected by securing a stiffening-bar permanently upon the upper 15 side of the blade and providing such bar intermediate to its ends with a part having tapering dovetail edges, such part being made of suitable length to receive the foot of the handle-bracket, while the opposite ends of 20 the bar are made with parallel edges and of the same width, respectively, as the top and bottom of the dovetail portion. The foot of the handle-bracket is secured to the stiffening-bar detachably by means of a dovetail 25 adapted to wedge upon the tapering dovetail upon the middle of such bar. I have found that the dovetail upon the foot of the handle-bracket may be made either tapering or parallel and may be jammed upon the dovetail 30 portion of the stiffening-bar with sufficient firmness to hold the blade when in use by making only a slight taper upon the dovetail portion of such bar. With this construction the parallel dovetail in the foot of the bracket 35 may be made cheaply and rapidly by means of a milling or planing tool, and the bracket-foot with this construction is secured to the blade when in use without the need of employing set-screws or other fastenings liable 40 to distort the blade.

The handle may be removed from the trowel-blade by knocking the foot of the bracket loose from the dovetail upon the stiffening-bar, and the handle and blade may then be 45 laid together in much less space than would be occupied by the entire trowel.

The invention also includes a special construction for the handle-bracket by which it is stamped from sheet metal in two elbow-50 pieces of flat channel form which are united to form a vertical post with a foot extended from the front and back of the same. By

making the handle-bracket pieces of sheet metal they may be stamped to exactly the desired form with very little expense, and by 55 stamping the elbow-pieces of flat channel form they are provided with ribs which are readily bent to form the dovetail upon the foot without the labor of filing or grinding, which is necessary when the ordinary malleable-iron brackets are used. 60

The invention will be understood by reference to the annexed drawings, in which—

Figure 1 is a side elevation of the trowel with a wooden handle indicated by dotted 65 lines. Fig. 2 is an end elevation of the trowel. Fig. 3 is an end view, and Fig. 4 a side view in section, of the handle-bracket. Fig. 5 shows the under side of the handle-bracket. Fig. 6 is a plan of the trowel-blade and stiffening-bar. Fig. 7 shows the under side of the stiffening-bar upon a larger scale; and Figs. 70 8 and 9 are cross-sections of the stiffening-bar upon line 8 8 and line 9 9, respectively, in Fig. 7.

A designates the trowel-blade, with the stiffening-bar riveted upon the middle of the outer side. The stiffening-bar is formed with wide forward end B, a narrow rear end B', and an intermediate dovetail portion b. The 80 forward end B has parallel top edges, which in practice are extended along the edges of the dovetails b, and the rear portion B' has also parallel edges and is in practice made of the same width as the lower edges of the 85 dovetails. The bar is made of sheet-steel of the same grade as the blade A and is tempered in like manner and afterward secured to the blade by rivets C. The stiffening-bar is thus rendered highly elastic and is not 90 liable to take a "set" or permanent bend.

The handle-bracket, as shown particularly in Figs. 3 to 5, inclusive, is formed of two similar parts or halves, each half consisting of an elbow-piece of flat channel form resembling in cross-section a flat "channel-iron," having a flat body D with ribs E. The arms of the elbow-pieces are shown of unequal length, the longer arms being secured together by a rivet F with the ribs in contact, 95 as shown in Fig. 5, thus forming a hollow post, (designated I in Figs. 1 and 2,) which possesses great lightness and strength. 100

The shank G for the wooden handle H is

riveted through the top of the post, as shown in Fig. 4, thus stiffening and strengthening the post at the upper end. The shorter arms of the elbow-pieces project in the same plane 5 in opposite directions from the bottom of the post, thus forming a flat bracket-foot, (designated J in Figs. 1 and 2,) provided with ribs upon its under side.

To fit the handle-bracket for application to 10 the stiffening-bar, the ribs of the foot are inclined inwardly to form a dovetail adapted to fit the dovetail edges *b* of the stiffening-bar. The dovetail upon the foot may be made by bending the ribs upon the edges of 15 the lower bracket-arms into contact with a steel former having the same shape as the dovetail portion of the stiffening-bar, or the ribs, after stamping at right angles like those upon the upper arms of the bracket, may be 20 ground or milled out by a revolving tool, thus forming a parallel dovetail groove upon the under side of the foot. If such a parallel groove upon the foot of the bracket were applied to the parallel dovetail edges upon the 25 stiffening-bar, it could not be retained thereon without some fastening device, which would be liable to spring the bar and the trowel-blade, and to avoid the use of such fastening device I form the dovetail edges *b* of the bar 30 with a slight taper, as indicated in Figs. 7, 8, and 9, so that the bracket when crowded upon the stiffening-bar may be retained thereon by friction.

I have found by experience that a parallel 35 dovetail groove in the foot of the bracket may be jammed firmly upon the tapering dovetail edges of the stiffening-bar and will be retained thereon in a suitable manner while the trowel is in use, while the construction 40 permits the bracket-foot to be knocked or pushed longitudinally from such stiffening-bar whenever it is desired to detach the handle from the blade.

By making the rear portion of the stiffening-bar without any dovetail and narrow 45 enough to enter readily the groove in the foot of the bracket it facilitates the application of the foot to the dovetail portion of the bar by guiding the same thereon. The forward portion 50 of the stiffening-bar is made without dovetail edges and wide enough to resist the movement of the bracket-foot beyond the forward ends of the dovetail edges, thus preventing the handle-bracket from being crowded 55 gradually forward and thus wearing or loosening it upon the bar. I find in practice that the tempered stiffening-bar *B B'* serves, when combined with the bracket-foot in the manner described, to hold the trowel-blade perfectly flat, as no set-screws or clamping devices are present to warp or spring the blade. I also find that the parts of the handle-bracket 60 can be made very cheaply of sheet-steel by a stamping operation, which produces them of very light weight and smooth surface and which saves a great deal of labor in grinding and polishing, while the ribbed form of the

elbow-pieces furnishes a very stiff construction.

By making the handle-bracket of sheet 70 metal the ribs which form the dovetail groove upon the foot can be cheaply fitted to the required shape without the filing and dressing which is required to make a close joint, as is necessary with the malleable-iron brackets 75 largely used for similar constructions.

By making the shank *G* for the wooden handle separate from the handle-bracket and riveting it thereon I find that a handle-bracket can be finished up and polished much more 80 readily than where the shank is formed integral therewith, as with the ordinary malleable-iron brackets. The whole construction is very cheap, while it furnishes great 85 stiffness to the trowel and holds the trowel-blade in an improved manner.

A great advantage exists in making the handle detachable from the trowel-blade, as a much greater number of the trowels can be packed in a case of given size for transportation, and my invention furnishes a most effective and useful means of making the handle 90 detachable, while it supports the blade in use without distorting the form of the same.

It will be observed that the stiffening-bar 95 is secured upon the trowel-blade *A* midway of its length and breadth, but that the dovetail portion of the stiffening-bar is much nearer to the wide end *B* than to the narrow end *B'*, as the handle-bracket is necessarily 100 attached to the forward end of the handle. Furthermore, by the method of construction the foot of the handle-bracket projects forward and backward from the post *I*, as shown in Fig. 1, the forward projection thus necessitating a forward extension of the dovetail. I have therefore made special claim to a 105 stiffening-bar having the dovetail near the forward end, with the other end contracted in the rear of the dovetail to facilitate the 110 application of the bracket-foot.

Having thus set forth the nature of my invention, what I claim herein is—

1. In a plastering-trowel, the combination with the trowel-blade of a handle-bracket 115 formed in two halves, each half consisting of an elbow-piece of flat channel form, the corresponding arms in the two elbow-pieces being secured together with the edge ribs in contact to form a vertical post and to receive 120 the shank of the handle, and the remaining arms projecting in the same plane to form a flat foot for attachment to the trowel-blade, substantially as herein set forth.

2. In a plastering-trowel, the combination 125 with the trowel-blade, having a dovetail stiffening-bar as set forth, of a handle-bracket formed in two halves, each half consisting of an elbow-piece of flat channel form, the corresponding arms in the two elbow-pieces being secured together with the edge ribs in contact to form a vertical post and to receive 130 the shank of the handle, and the remaining arms projecting in the same plane and hav-

ing the ribs inclined to form a flat foot with dovetail groove upon the under side for attachment to the dovetail bar, substantially as herein set forth.

5 3. In a plastering-trowel the combination, with the trowel-blade of a stiffening-bar having, intermediate of its ends, a portion provided with dovetail edges, and having a handle-bracket formed in two halves, each half 10 consisting of a sheet-metal elbow-piece of flat channel form, the corresponding arms of the two elbow-pieces being secured together with the edge ribs in contact to form a vertical post and to receive the shank of the handle, and the remaining arms forming a flat foot 15 with the ribs upon the same inclined to fit the dovetail portion upon the said stiffening-bar, substantially as herein set forth.

4. In a plastering-trowel, the combination, 20 with the trowel-blade, of a stiffening-bar having a forward portion and intermediate portion of the same width, with dovetail edges upon such intermediate portion, and a narrower rear portion adapted to guide a dovetail foot-piece upon the intermediate portion, and a handle having foot with dovetail groove 25 to fit the bar, substantially as herein set forth.

5. In a plastering-trowel, the combination,

with the trowel-blade, of a stiffening-bar having a forward portion and intermediate portion of the same width, with dovetail edges upon such intermediate portion, a parallel rear portion of less width than the intermediate portion, and a handle having a bracket with dovetail groove in the foot 30 35 adapted to fit the dovetail edges of such stiffening-bar, and to be guided upon the same by the rear portion of such bar, as and for the purpose set forth.

6. In a plastering-trowel, the combination 40 with a trowel-blade of a stiffening-bar attached to the blade midway of its length and breadth, and formed with the short forward portion B, the intermediate portion having tapering dovetail b upon its edges, and the 45 narrower rear portion B' of greater length than the portion B, and a handle with foot having dovetail groove, as and for the purpose set forth.

In testimony whereof I have hereunto set 50 my hand in the presence of two subscribing witnesses.

JAMES HILTON.
